CLAIM

The ornamental design for a grip-head handle, as shown and described.

DESCRIPTION

FIG. 1 is a front, left, top perspective view of a grip-head handle showing my new design, the support shown in broken lines for illustrative purposes only and forms no part of the claim;

FIG. 2 is a left side elevational view thereof, the right side elevational view being a mirror image;

FIG. 3 is a front elevational view thereof;

FIG. 4 is a top plan view thereof;

FIG. 5 is a bottom plan view thereof; and,

FIG. 6 is a rear elevational view thereof.
